COLUMBUS JOHNSTON, OF CLARKSVILLE, MISSOURI.

Letters Patent No. 68,512, dated September 3, 1867.

IMPROVEMENT IN CHARGER FOR SHOT-POUCHES.

The Schedule referred to in these Letters Patent and making part of the same.

TO ALL WHOM IT MAY CONCERN:

Be it known that I, COLUMBUS JOHNSTON, of Clarksville, Pike county, Missouri, have invented a new and useful Improvement in Chargers for Shot-Pouches; and I do hereby declare that the following is a full, clear, and exact description thereof, which will enable others skilled in the art to make and use the same; reference being had to the accompanying drawings, forming part of this specification.

The present invention relates to a charger for shot-pouches, which charger is constructed with two tubes, one arranged to slide within the other, and with the outer one provided with an opening communicating with the pouch, and an opening communicating with the discharge-spout or tube, and with the inner so constructed and arranged that by pushing or forcing it in, the opening to the pouch is closed at the same time the opening to the discharge-tube is being opened. The shot contained within the inner tube between the openings of the outer and discharge-tubes can pass to the discharge-tube, and thence out of it to and into the barrel of the gun, if properly presented thereto. The inner tube of the charger is constructed in such a manner as to enable a greater or lesser number or amount of shot to be discharged from the pouch, as may be desired. In the accompanying plate of drawings my improvements in chargers for shot-pouches are illustrated—

Figure 1 being a central section through the same in the direction of its length, and

Figure 2 a transverse section in the plane of the line x , fig. 1.

Similar letters of reference indicate corresponding parts.

A and B, in the drawings, represent two concentric tubes, the one, A, within the other, B, wherein it is arranged to slide or play in and out. C, a spiral spring in the outer tube B, between its end or head-plate D and the inner end E to the inner tube, this spring acting to throw out the inner tube and so hold it. To one side of the outer tube B the pouch is secured in any suitable manner, and between the two communication is had by an opening, F, in the corresponding side of the tube. G, an opening in inner tube corresponding to the opening of the outer tube. Below the opening F in the outer tube, and upon the opposite side of the same thereto, is an opening, H, communicating with the side discharge-tube or spout I. The opening or part H is closed when the inner tube is out to its greatest distance, a pin or projection, J, of such tube limiting and stopping its outward movement by contact with the upper end of the part H.

With a charger constructed as above described the shot pass from the pouch through the opening F of the outer tube into the same, filling its space or chamber L, when, pressing in the inner tube A, the shot are carried down by its head or partition-plate N to the lower opening H of the tube, which is being opened by such movement, through which opening they pass out into the discharge-tube I, the pouch-opening F closing as the spout-opening opens.

To regulate the capacity of the charger for receiving and delivering a greater or lesser amount of shot, the inner tube is provided with a plunger or partition-plate, N, that through its stem O is connected with a cap, P, to the tube. This cap has a spiral slot, Q, by which it turns or moves upon a stud or pin, R, of the tube A. This slot is notched at four points, S, which are respectively marked according to the capacity of the charger when the pin R is in this or that notch, as, for instance, quarter ounce, half ounce, three-quarter ounce, etc.

I claim as new, and desire to secure by Letters Patent—

1. The combination of the inner and outer tubes A and B, having side ports and side discharge-tube I, when all arranged together substantially as and for the purpose described.
2. I also claim the adjustable plunger or piston-head N to the inner tube A, substantially as described, for the purpose specified.

COLUMBUS JOHNSTON.
